UNITED STATES PATENT OFFICE

2,107,687

DOOR LATCH

William Edward Brown, Oakland, Calif.

Application May 4, 1937, Serial No. 140,763

2 Claims. (Cl. 292—78)

This invention relates to pivoted latches designed primarily for use in securing closet doors or the like, in their closed positions.

An important object of the invention is to provide a latch of this character which will securely hold the closure or door in its closed position, but will permit the closure to swing open when force is directed to the closure in pulling the closure open.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a transverse sectional view through a closure and its frame, illustrating a latch constructed in accordance with the invention, as mounted within the closure frame.

Figure 2 is a front elevational view of the latch.

Figure 3 is a view of the keeper plate, used in connection with the latch.

Figure 4 is an end elevational view of the latch.

Figure 5 is a vertical sectional view through the latch illustrating the pivoted latch member 30 in its active position.

Figure 6 is a sectional view through the latch, illustrating the latch member as moved to its inactive position, when the closure is being moved to close the closet or cupboard of which it forms 35 a part.

Figure 7 is a sectional view through the latch illustrating the position of the latch member when the closure is moved in the direction indicated by the arrow, to open the closure.

Figure 8 is a sectional view through the upper portion of the latch frame.

Figure 9 is a perspective view of the link which pivotally connects the latch member to its frame.

Referring to the drawing in detail, the reference character 5 designates a portion of the frame in which the closure 6 operates. The section 5 of the frame, is cut out to accommodate the latch indicated by the reference character 7. This latch includes the securing plate 8 formed with 45 openings to accommodate securing screws, whereby the plate may be secured within the cut out portion. The reference character 9 indicates the latch frame, that is secured to the plate 8 and extends therefrom, as clearly shown by Figure 5 50 of the drawing. The frame embodies spaced side

walls 10, between which the latch member 11 operates, the latch member extending through an opening in the plate 8, as clearly shown by the drawing.

This latch member 11, is formed with a curved 5 surface 12, and a substantially straight edge 13 extending at an oblique angle with respect to the edge 14 that is disposed within the latch frame, under normal conditions. The straight edge 13 is so formed that an extension 15 is provided at 10 one end of the latch member 11, the extension defining a shoulder which rests against the plate 8, normally holding the latch member within the frame.

An opening is formed in the latch member 11, 15 near the upper edge thereof, the opening being designed to accommodate the section 16 of the U-shaped link 17, the link having right-angled end portions 18 extended in opposite directions, to fit within the openings 19, formed in the side 20 walls of the latch frame.

Extending transversely through the latch frame, is a pin indicated by the reference character 20, which pin provides a support for the spring member 21, which is formed of a length 25 of wire material, bent upon itself to provide a wide latch member engaging portion 22, and arms 23, the arms 23 having their free ends disposed in notches 24 formed in the latch frame, as shown by Figure 5 of the drawing. The intermediate 30 portions of the spring member, are coiled around the pin 20, in such a way as to lend resiliency to the spring member, and at the same time securely mount the spring member within the latch frame.

From the foregoing it will be seen that due to 35 the construction shown and described, the keeper plate, which is indicated by the reference character 25, and which is carried by the closure, will contact with the latch member 11, when the closure is moved to its closed position, moving the 40 latch member into the latch frame, or to the position as shown by Figure 6 of the drawing.

When it is desired to move the closure to its open position, the closure is pulled in the usual way. It follows that the keeper plate 25 moving 45 against the curved edge of the latch member 11, will cause the latch member to move inwardly, and assume a position as shown by Figure 7, releasing the closure to allow the closure to be moved to its open position.

Having thus described the invention, what is claimed is:

1. A latch for latching hinged closures, comprising a frame having an opening, a latch member pivotally mounted within the frame and ex- 55

tended through the opening, a substantially U-shaped link pivotally connected to the latch member near one end thereof and having right-angled ends fitted in openings formed in the side walls of the frame near the opposite end of the latch member, a spring member mounted within the frame and bearing against the latch member at a point between the pivot points of the link, whereby the latch member will move inwardly when the closure is moved to either its open or closed position.

2. A latch for latching hinged closures, com-

prising a latch frame having an opening, a latch member extended through the opening, a U-shaped link pivotally connected with the latch member, said U-shaped link having right-angled ends fitted in openings formed in the frame, pivotally mounting the latch member within the frame whereby the latch member will move into the frame when the closure with which the latch member is used, is swung to its open or closed position, and means for normally urging the latch member to its active position.

WILLIAM EDWARD BROWN.
